DATA PROCESSING SYSTEM OPERATOR'S STATION

Clarence F. Graser and Walter F. Kraus, Poughkeepsie,
and William S. Sheppley, Jr., Rhinebeck, N.Y., assign-
ors to International Business Machines Corporation,
New York, N.Y., a corporation of New York

Filed July 18, 1962, Ser. No. 70,972

Term of patent 14 years

(Cl. D26—5)

FIG. 4

Des. 194,845

PAGE 2

FIG. 2

FIG. 3

FIG. 1 is a perspective view of the front and left hand side of a data processing system operator's station showing our new design,

FIG. 2 is a perspective view of the rear and right hand side thereof, and,

FIG. 3 is a plan view of the data processing system operator's station.

We claim:

The ornamental design for a data processing system operator's station, substantially as shown.
